UNITED STATES PATENT OFFICE.

HERMAN O. PORTER, OF ROCHESTER, NEW YORK.

RADIATOR COVER.

1,402,651.

Specification of Letters Patent. Patented Jan. 3, 1922.

Application filed August 14, 1919. Serial No. 317,480.

To all whom it may concern:

Be it known that I, HERMAN O. PORTER, a citizen of the United States, residing at Rochester, in the county of Monroe and 5 State of New York, have invented certain new and useful Improvements in Radiator Covers, of which the following is a specification.

This invention relates to protectors for hot 10 water and steam radiators.

The object of the invention is to provide a simple and efficient cover for radiators of the class described, which will prevent freezing of the water in said radiators when exposed to low temperatures, such as obtain in 15 sleeping rooms, in cold climates when the windows are left open for ventilation.

Another object is to construct a protector of this class which may remain continuously 20 over the radiator and yet permit heat to pass out therethrough at the will of the occupant of the room in which the radiator is placed.

With the foregoing and other objects in view, which will appear as the description 25 proceeds, the invention resides in the combination and arrangement of parts and in the details of construction hereinafter described and claimed, it being understood that changes in the precise embodiment of the invention herein disclosed may be made within 30 the scope of what is claimed without departing from the spirit of the invention.

In the accompanying drawings:—

Figure 1 represents a front elevation with 35 parts broken out of a radiator cover constructed in accordance with this invention with the closure in closed position,

Fig. 2 is a horizontal section with the closure shown closed in full lines and open 40 in dotted lines, and

Fig. 3 is a perspective view showing a different form of the invention applied.

In the embodiment illustrated in Figures 1 and 2, a radiator R of ordinary construction 45 such as is used for hot water or steam is shown, and over which is placed a casing 1 of any suitable material, preferably of ornamented metal, although obviously it may be of other material. This casing 1 is shaped 50 to conform to the shape of the radiator and fits snugly against the floor F, completely encompassing the radiator. The front wall of the casing 1 has an opening therein equipped with a slatted closure, the slats 3,

which are pivotally mounted at their ends 55 in the upper and lower edges of the opening in the casing as shown at 4. These slats 3 are similar to pivoted slats or window shutters, registers and the like, and when 60 closed assume the position shown in full lines in Fig. 2, forming an airtight closure for the casing.

A rod 5 is pivotally connected with the outer faces of the slats 3, being shown 65 equipped with a plurality of eyes 6 which are loosely engaged with similar eyes 7 carried by the slats 3. This rod 5 has a hand grip 5^a positioned for convenient actuation and which is shown clearly in Fig. 1. 70

Each of the slats 3 has secured to its inner face a non-conducting lining 8 of asbestos or similar material which will prevent the passage of heat out through the slats or the entrance of cold. 75

Coiled springs 9 are connected at one end with the slats 3 on their inner faces, and at their other ends are connected with the rod 10 which extends longitudinally through the casing 1 at a point spaced inwardly from 80 the wall having the opening therein. These coiled springs are positioned obliquely and are connected with the free edges of the slats, and exert their tension to normally hold the slats in closed position as shown in 85 full lines in Fig. 2.

The protector, 1, when placed over a radiator as shown in Fig. 1, and the slats 3 closed, will completely encompass the radiator and exclude from the casing all cold air, 90 such as would tend to freeze the contents of the radiator should the temperature drop to an extreme limit.

When it is desired that heat shall pass out from the casing, the slats are opened by a 95 single pull exerted on the handle 5^a of rod 5 thereby opening the slats at right angles to the casing into the dotted line position shown in Fig. 2, and which may be held in this position against the tension of springs 9 by 100 any suitable means, not shown.

In the form shown in Fig. 3, a removable casing 1^a is shown composed of any suitable material, flexible, rigid, or not, and which is lined with a non-conducting material 2^a, 105 similar to the lining 2 shown in the other figures. This casing 1^a is designed to be placed over the radiator R at night, when the window W above it is opened, and thus

protect the radiator against extremely cold temperature. In the morning when the window is closed, this casing 1^a is removed to permit the radiator to dispel heat into the 5 surrounding atmosphere.

From the foregoing description, taken in connection with the accompanying drawings, the advantages of the construction and of the method of operation will be readily 10 apparent to those skilled in the art to which the invention appertains and while I have described the principle of operation of the invention together with the device which I now consider to be the best embodiment 15 thereof, I desire to have it understood that the device shown is merely illustrative and that such changes may be made as are within the scope of the claimed invention.

Having thus fully described my invention,

what I claim as new and desire to secure by 20 Letters Patent, is:—

A radiator cover comprising a casing shaped to encompass the entire radiator, one wall of said casing having an opening, a plurality of pivotally mounted slats positioned 25 in said opening and adapted to close it, a rod connecting said slats, a rod extending longitudinally of said casing and spaced from the wall having the opening therein, and a plurality of coiled springs each connected with 30 said rod and with one end of said slats.

In testimony whereof I affix my signature in presence of two witnesses.

HERMAN O. PORTER.
